HEAD AND LIME REST

Lillian Richards, Hollywood, Calif.

Application July 17, 1947, Serial No. 761,580

2 Claims. (Cl. 155—177)

1

This invention relates to a rest which may be used as a support for a person's head, arm, or leg, and may also be used by an invalid or a person reclining in bed for supporting a book being read. It will also be understood that the device may be used as a seat for a baby held in a person's lap and put to many other uses for which it may be found suitable.

One object of the invention is to provide a support consisting of a metal frame formed of sections pivoted to each other so that the support may be folded and easily carried or placed in a flattened condition upon a shelf or the like when not in use or a number of the improved supports folded and stacked when not in use.

Another object of the invention is to provide a support wherein the pivotally connected frame sections carry strips of fabric which are looped about end bars of the frame sections and each strip has its ends laced together so that it has inner and outer flights which are stretched tight when the frame sections are swung to an opened position.

Another object of the invention is to provide a support having a frame carrying looped strips or sheets of fabric which may be easily removed for washing and thus kept clean and sanitary and suitable for use in a hospital or convalescent home.

Another object of the invention is to provide a support wherein the pivoted sections of the frame are provided with braces of the brake-joint which brace the frame when in the opened position and are adjustable so that the extent to which the frame is opened may be controlled and its height thus adjusted.

Another object of the invention is to provide a device of this character which is simple in construction and may be manufactured at small cost.

The invention is illustrated in the accompanying drawings wherein:

Fig. 1 is a side view of the improved rest.

Fig. 2 is a top plan view with portions of the fabric members broken away.

Fig. 3 is a sectional view taken along the line 3—3 of Figure 1.

Fig. 4 is a view showing the rest in its folded position.

Fig. 5 is a sectional view taken along the line 5—5 of Figure 4.

Fig. 6 is a view showing a fragment of the frame in perspective.

Fig. 7 is a perspective view showing a modified frame construction.

2

This improved support or rest is particularly adapted for use as a rest for an arm, foot or leg of an invalid or person who has been wounded and may also be very effectively used as a head rest, but it will be understood that it may be put to other uses for which it is found suitable. For instance it could be used when holding a baby and prevent overheating of the baby or the person holding the baby since the device will be placed upon the lap and the baby sit upon the device and thus allow circulation of air and prevent direct contact of the baby with the lap of the person holding the baby. It may also be used as a book rest and support a book in convenient position to be read without subjecting the person using it to objectionable weight.

The support or rest has a body formed of aluminum or other suitable light weight metal and consisting of companion rectangular frames 1 and 2 which are of such dimensions that the frame 2 will fit within the frame 1 when the device is in the collapsed position shown in Figures 4 and 5. Each frame is formed midway the length of its side bars with openings which register and through these openings are passed rivets 3 which hold the two frames in pivotal connection with each other and permit them to be swung to an extended or folded position. Braces 4 limit movement of the frames to an extended position, and these braces are of the brake-joint type and each formed of strips 5 which have their inner ends pivotally connected with each other by a rivet 6 and their outer ends pivotally held against inner side faces of the side bars of the frames by screws 7. The screws 7 are passed through selected ones of the openings 8 formed in the side bars of the frames, and from an inspection of Figure 1 it will be seen that by shifting the braces from one set of openings 8 to another the extent to which the frames may be moved about the pins 3 will be controlled and the height of the support or rest thus regulated. In order to provide space between the side bars of the frames to accommodate the braces when folded washers 9 may be applied to the pins 3 or the outer frame 1 may have its side bars bent outwardly as shown at 10 in Figure 7 and thus provide space to accommodate the folded braces. Slings 11 are carried by the frames and consist of strips of strong fabric which are trained about the end bars of the frames and have their ends folded and provided with eyes or grommets 12 through which laces 13 are threaded, as shown in Figure 2 and then tied in a bow knot 14. When the frames are moved to the extended position the strips of fabric forming the slings will be

stretched and provide soft slings upon which a foot, arm, leg or head may rest and be comfortably supported upon a wide surface of soft fabric. Since the slings are at upper and lower ends of the frames the device may be set in place for use with either end disposed upwardly and the strip of fabric at the bottom will assist in bracing the frames against opening movement beyond the desired extent. By loosening the laces the length of the upper and lower flights of the fabric strips may be controlled and the upper sling allowed to sag somewhat if so desired. When the strips of fabric become soiled the strips of fabric may be removed and laundered and sterilized and then replaced. If the support is used as a book rest the lower strip of fabric may rest upon the chest or abdomen of a person in reclining position and a book set at rest upon the upper strip where it will be held in position to be conveniently read. When the device is used as a support for a head, leg or arm air may circulate freely and prevent discomfort by heat which is present when a pillow is used.

Having thus described the invention, what is claimed is:

1. A support comprising inner and outer rectangular frames formed of stiff metal and each having upper and lower end bars and side bars integrally connected with and of greater length than its end bars, said inner frame passing through said outer frame and having its side bars pivoted to the side bars of the outer frame by fasteners passing through aligned openings formed in the side bars of said frames midway the length thereof, the upper portions of the side bars being formed with a plurality of openings spaced from each other longitudinally thereof, braces for limiting opening movement of the frames consisting of strips having inner ends pivotally connected in overlapped side by side relation to each other and having their outer ends disposed against confronting side faces of the side bars of said frames and pivotally mounted by removable fasteners passing through selected ones of the openings in

the side bars, said braces when folded extending longitudinally of the frames between upper portions of their pivotally connected side bars, and strips of flexible fabric trained about end bars of the frames and forming upper and lower flights and each having its end extending towards each other and adjustably connected by laces.

2. A support comprising inner and outer frames each having upper and lower end bars and side bars extending between its end bars, said inner frame passing through said outer frame and having its side bars pivoted to the side bars of the outer frame, said frames being adapted for pivotal movement from a folded position to an extended position in crossed relation to each other, a brace having one of its ends pivoted to a side bar of one of said frames, means for detachably and adjustably connecting the other end of said brace to the contiguous side bar of the other frame, and a strip of flexible fabric trained about end bars of said frames and forming upper and lower flights and having its ends extending towards each other, and means adjustably and detachably connecting ends of said strip.

LILLIAN RICHARDS.
